TIPPING MOTION FOR AXMINSTER LOOM

Filed April 27, 1938

FIG. 1

FIG. 2

UNITED STATES PATENT OFFICE

2,169,327

TIPPING MOTION FOR AXMINSTER LOOMS

William W. Robertson, Northboro, Mass., assignor to Crompton & Knowles Loom Works, Worcester, Mass., a corporation of Massachusetts

Application April 27, 1938, Serial No. 204,637

8 Claims. (Cl. 139—9)

This invention relates to improvements in tipping motions for Axminster looms and it is the general object of the invention to provide means for preventing the operation of the tipping motion if the tube frame fails to leave the transporting chain.

Axminster looms operate with a series of yarn tube frames which are moved to transfer position one at a time by transporting chains. The tube frames are connected to the chain by detachable latches or hooks which are disconnected when the tube frame is about to move from the chain to cloth forming position. The disconnecting is effected by means of clutches carried by operating arms or levers, the motion of the clutches being first inward to release the tube frame from the chain and then downward toward the cloth.

When the tube frame reaches the warp threads it must be given a rolling motion in order to insert the yarn tubes and the colored yarn projecting from them between the warp threads. This rolling motion is made possible by pivoting the clutch or carrier for the tube frame on the transfer arms and imparting angular motion to the clutches by mechanism acting in timed relation with the transfer arms. At the beginning of the rolling-in operation the yarn tubes assume a position approaching a horizontal, after which they are moved downwardly toward a more vertical position. The rolling of the clutches and tube frame is effected by a force transmitted through a rod pivoted to the clutches and receiving its driving force from a source independent of that which drives or controls the transfer arms. From this it will be seen that if the transfer arms are held raised by failure of the tube frame to become disconnected from the transporting chains, the rods connected to the clutches will be acted on to carry out the rolling operation. Under these conditions with the tube frame still connected to the transporting chain and therefore unable to move angularly the clutches and tube frame, together with the operating parts for the clutches, will be subjected to a strain which may bend them and prevent subsequent correct operation.

It is an important object of my present invention to provide a control for the rolling of the tube frame which will prevent transmission of a rolling force to the clutches when the transfer arms are raised even though the time in the cycle of the loom be reached at which rolling would ordinarily occur.

It is another object of my present invention to

control the clutch rolling mechanism by the transfer arm in such a way that movement of the arm must take place before the actuator for the rolling operation can be connected to the clutches. The mechanism for accomplishing this result as set forth hereinafter includes an L-shaped slotted rod head which reciprocates normally but is out of driving connection with respect to the clutch due to the raised position of the transerrer arms. When the latter move down they release the slotted member which then moves into driving relation with the clutch.

Axminster looms as heretofore made have frequently been provided with the stopping mechanism shown in Striemer Patent No. 1,546,685 which operates to stop the loom when a tube frame sticks to the chains. While I contemplate the use of the Striemer motion, it is found, nevertheless, that with increased speeds bending of the tube frame rolling mechanism and its connectors takes place before the Striemer mechanism can stop the loom.

With these and other objects in view which will appear as the description proceeds, my invention resides in the combination and arrangement of parts hereinafter described and set forth.

In the accompanying drawing, wherein a convenient embodiment of my invention is set forth:

Fig. 1 is an end elevation of the upper part of an Axminster loom having my invention applied thereto,

Fig. 2 is a rear elevation taken in the direction of arrow 2, Fig. 1,

Fig. 3 is a view similar to a portion of Fig. 1 but with the tube frame in cloth forming position,

Fig. 4 is a detail showing the L-shaped slotted actuator for the tube frame rolling mechanism, and

Fig. 5 is an enlarged detail front elevation of a clutch and one end of a tube frame released from the transporting chain, looking in the direction of arrow 5, Fig. 1.

Referring to the drawing, the loom frame 10 supports a cam shaft 11 which is geared in well-known manner to have one revolution for three beats of the loom for so-called three-shot Axminster fabric, but the invention to be set forth hereinafter is not limited to that particular type of fabric. In the upper part of the structure 45 there is shown a tipping or tube frame transfer shaft 12 having two arms 13 one of which is shown in Fig. 1. This shaft and its arms are operated through a vertical connector 14 deriving its force from suitable and well-known mecha-

- nism not shown every third beat of the loom, the effect of the rod being to lower the arms 13 and turn the shaft 12 in a counter-clockwise direction as viewed in Fig. 1 during the tuft forming beat of the loom.
- A transfer lever 15 is pivoted as at 16 to each arm 13 and has a rear arm 17 connected to a link 18. The lever 15 also has a front arm 19 extending to the left as viewed in Fig. 1 to have pivoted thereto as at 20 one of the two clutches 21 customarily found in Axminster looms. The clutch is therefore mounted so that it can move toward and from the tube frame T by rocking of the lever 15 in a horizontal plane around its pivot 16 under action of the well-known links 18. Connected pivotally to the clutch as at 22 is a rolling rod 23 extending rearwardly from the clutch and connected as at 24 to a rolling arm 25 supported by a tipping or rolling shaft 26.
- The matter thus far described, except for modifications to be set forth hereinafter, may be of common construction. The tube frames, one of which is shown in the drawing, are mounted on a transporting chain C which is given a step by step motion to bring the tube frames one at a time to the transfer position shown in Fig. 1. When in this position the tube frames T with the yarn tubes 27 extend downwardly with the yarn Y projecting therefrom. The yarn spool S supplies the yarn Y and is supported by the tube frame so that it moves with the latter toward the cloth board 28 during the tuft forming beat of the loom. The yarns Y must be dipped through the warp sheds W in order to form the Axminster loop, and this dipping is accomplished by angular motion of the clutch relatively to arm 19. In all essential respects the clutch, tube frame, chain and transfer arms 15 will be of well-known construction.
- The clutch has a rib 28 which overhangs a projection 29 on the tube frame when the clutch is in the releasing position shown in Fig. 5. As arm 19 of lever 15 starts down the hook 30 will ordinarily be free from the chain C. Should the clutch fail to release the hook, however, due to a defect of the hook or other reason, the rib will rest on the projection 29 and descent of arm 19 will be arrested. This relation of the rib and projection of itself is old, as shown in the Strie- 50 mer patent. With the tube frame still connected to the chain and held also by the clutch, angular motion of the latter would injure the tube frame. My present invention provides an actuating and controlling mechanism for the rod 23 to prevent it from transmitting rolling or tipping forces to the clutches if the arm 19 is raised.
- In carrying my invention into effect I extend the arm 25 rearwardly as at 40 and secure there- 60 in a pin 41 which projects into a vertical slot 42 formed in a rod head 43 adjustably secured to the upper end of a vertical actuator rod 45. A second slot 44 extending horizontally from and communicating with slot 42 is normally hori- 65 zontally aligned with the pin 41, while slot 42 is normally aligned vertically with the pin.
- The lower end of rod 45 is pivoted as at 50 to a lever 51 movable about a fixed pivotal support 52 mounted on the loom frame and carry- 70 ing a roller 53 to engage a cam 54 supported by shaft 11. A spring 55 is connected between the lever 51 and a clip 56 adjustably secured on the rod 45. The effect of the spring 55 is to tend to move the rod 45 to the right as viewed in Fig. 75 1 for the purpose of placing a lifting shelf 57

on the rod head 43 under the pin 41. Slot 44 permits this shift under the action of the spring.

The control for the rod head 43 is exercised through the shaft 12 which, as shown in Fig. 1, has a downwardly extending arm 60 into which 5 is threaded an adjustable pressure screw 61 shown in Fig. 2 as positioned to engage the rear of the rod head 43. Movement of the screw 61 to the left as viewed in Fig. 1, or forwardly, moves the slot 42 in vertical alignment with the 10 pin 41, whereas movement of the screw 61 rearwardly or to the right permits the spring 55 to shift the rod head 43 to the right and place lifting shoulder 57 under the pin 41.

In normal operation of the loom, the lever 15 15 will move the clutch to the position of Fig. 5 to disconnect the tube frame from the chain, after which rod 14 will descend toward cloth forming position indicated in Fig. 3. During this descent cam 54 will raise lever 51 to elevate rod 20 45. Downward motion of levers 13 and 15 is accompanied by a motion of screw 61 to the right so that spring 55 can move the rod head 43 to the position shown in Fig. 3. Upward motion of rod 45 therefore rocks lever 25 around 25 the axis 26 to move the rod 23 to the left, or forwardly as viewed in Fig. 1, and effect a rocking of the clutch so that the same assumes the dotted line position shown in Fig. 3. The rod 23 is immediately thereafter retracted, by the 30 weight of lever 51, during an upward motion of the lever 15 to cause the tube frame to assume the position shown in full lines in Fig. 3. The angular motion of the clutch and tube frame around the center 20 is determined by cam 35 54, and is the well known "wiping-in" operation of the tube frame.

If for any reason the tube frame is not unclutched from the chain C the lever 15 will be held up, as will be understood from Fig. 5, 40 and screw 61 will hold the rod 43 in such position that the vertical slot 42 is under pin 41 and motion of rod 45 upwardly will not rock lever 25. Rod 23 will therefore not tend to rock the clutch and the parts will not be subjected 45 to any strain. The loom will then be stopped by the Strie- 50 mer stop motion in common use. Although the weight of lever 51 is relied upon to move the rod 23 in a right hand direction as viewed in Fig. 1 to restore the clutch to normal 50 vertical position, I do not wish necessarily to be limited to this mode of operation, inasmuch as the usual means such as a spring not shown can be used to turn the shaft 26 in a clockwise direction for the retraction of rod 23, as is cus- 55 tomary in Axminster looms.

From the foregoing it will be seen that I have provided a simple form of drive to effect the rolling operations of the clutch 21 and have placed the drive under control of the shaft 12. 60 If for any reason this shaft is held raised so as to make angular motion of the clutch 21 undesirable, the rod 45 will be in such a position that it cannot actuate lever 25. If, on the other hand, the tube frame has descended to the positions 65 shown in Fig. 3, the rod head 43 moves to the right and the lifting shoulder or surface 57 moves under the pin 41 and rolling operation of the clutch can take place.

Having thus described my invention it will 70 be seen that changes and modifications may be made therein by those skilled in the art without departing from the spirit and scope of the invention and I do not wish to be limited to the details herein disclosed, but what I claim is: 75

1. In an Axminster loom having transporting chains carrying a tube frame, a transfer arm movable from the transporting chains toward the cloth being woven on tuft forming beats of the loom, a tube frame engaging clutch pivoted to the arm, actuating mechanism for the clutch to move the latter angularly with respect to the arm, and a controller for the actuator positioned by the transfer arm to prevent the actuator from moving the clutch angularly when the transfer arm fails to move to tuft forming position on tuft forming beats of the loom. 5
2. In an Axminster loom having a transporting chain and a tube frame detachably connected thereto, transfer means to detach the tube frame from the chain and convey said tube frame to cloth forming position on tuft forming beats of the loom, a pivotal connection between the tube frame and the transfer means, an operating lever 10 movable about a fixed pivot, a cam to operate the lever positively in one direction, connections between the lever and the tube frame for rocking the same about said pivotal connection, said connections including two parts for mutual cooperation but normally out of cooperating position, and means under control of the transfer means to cause said parts to cooperate prior to movement of the operating lever by the cam. 15
3. In an Axminster loom having a tube frame 20 to be moved to cloth forming position on tuft forming beats of the loom, a transporting chain to which the tube frame is detachably connected, transfer means to detach the tube frame from the chain and convey said tube frame to cloth forming position on tuft forming beats of the loom, mechanism to move the tube frame angularly with respect to the transfer means on tuft forming beats of the loom, an operating lever 25 movable about a fixed pivot, a cam to actuate said lever positively, and means controlled by the transfer means to connect the operating lever to said mechanism when the transfer means moves the tube frame toward cloth forming position. 30
4. In an Axminster loom having a transporting chain and a tube frame detachably connected thereto, transfer means to detach the tube frame from the chain and convey said tube frame to cloth forming position on tuft forming beats of the loom, means to connect the tube frame and transfer means to prevent the latter from moving to cloth forming position when the tube frame fails to be detached from the transporting chain on tuft forming beats of the loom, mechanism to 35 give the tube frame rolling-in movements relatively to the transfer means on tuft forming beats of the loom, an actuator lever for the mechanism movable about a fixed pivot, means to actuate said lever on tuft forming beats of the loom, and connections between the actuating lever and the mechanism controlled by the transfer means and effective when said transfer means moves to cloth forming position to transmit a force from the actuating lever to the mechanism and effective when the transfer means fails to move to cloth forming position on tuft forming beats of the loom to prevent a force from being transmitted from the actuating lever to said mechanism. 40
5. In an Axminster loom having a transporting chain and a tube frame detachably connected thereto, transfer means to detach the tube frame 45 from the chain and convey said tube frame to cloth forming position on tuft forming beats of the loom, arresting means to connect the tube frame and transfer means to prevent the latter from moving to cloth forming position when the tube frame fails to be detached from the transporting chain on tuft forming beats of the loom, mechanism to move the tube frame angularly relatively to the transfer means on tuft forming beats of the loom, and means controlled by the transfer means and including a lever movable about a fixed pivot to prevent operation of the mechanism when the transfer means is prevented by the arresting means from moving to cloth forming position. 50
6. In an Axminster loom having a transporting chain carrying a tube frame to be detached therefrom on tuft forming beats of the loom, transfer means to disconnect the tube frame from the chain and convey said tube frame to cloth forming position on tuft forming beats of the loom, a pivotal connection between the tube frame and the transfer means, mechanism normally operative to move said tube frame about said pivotal connection on tuft forming beats of the loom, and means controlled by the transfer means and including a lever movable about a fixed pivot to prevent operation of the mechanism when the transfer means fails to convey the tube frame to cloth forming position on tuft forming 55 beats of the loom. 60
7. In an Axminster loom having transporting chains carrying a tube frame to be detached therefrom on tuft forming beats of the loom, a transfer arm to detach the tube frame from the chains and move with the tube frame toward tuft forming position, a clutch pivoted to the transfer arm to engage the tube frame, a two-part actuator for said clutch one of which parts moves regularly on tuft forming beats of the loom and the second of which parts is moved by the first part, means including a lever movable about a fixed pivot to move the first named of said parts, and means positioned by the transfer arm to prevent cooperation of said parts when the transfer arm fails to move toward cloth forming position. 65
8. In an Axminster loom having a transporting chain, a tube frame detachably connected to the tube frame, transfer means normally operative on tuft forming beats of the loom to detach the tube frame from the transporting chain and convey said tube frame to cloth forming position, an actuator having an actuating motion on tuft forming beats of the loom, force transmitting means normally out of the path of the actuator and connected to the tube frame to move the latter angularly with respect to the transfer means when moved by the actuator, a controller for the actuator positioned by the transfer means to cause said actuator to be normally out of the path of said force transmitting means when the transfer means is adjacent to the chain, and additional means to move the actuator into operative relation with respect to the force transmitting means on tuft forming beats of the loom when said controller moves out of controlling position with respect to the actuator due to motion of the transfer means from the transporting chain toward cloth forming position. 70
